Primary Examiner — Mark A Goodwin(74) *Attorney, Agent, or Firm* — Fitch, Even, Tabin & Flannery LLP**CLAIM**

The ornamental design for a blower, as shown and described.

DESCRIPTION

FIG. 1 is a perspective view of our new design of a blower; FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a bottom plan view thereof.

The broken lines depict portions of the blower that form no part of the claimed design.
